United States Patent Office

Des. 180,866
Patented Aug. 27, 1957

180,866

PONTOON BOAT

Howard K. Dearborn, Berea, Ohio

Application July 23, 1956, Serial No. 42,348

Term of patent 14 years

(Cl. D71—1)

Fig. 1

Fig. 2

Fig. 4

Fig. 3

Fig. 1 is a side perspective view of a pontoon boat, showing my new design with the wheels illustrated in lowered position;

Fig. 2 is a front view in perspective of said boat; Fig. 3 is a rear perspective view of the said boat; and Fig. 4 is a front elevational view of the boat.

I claim:

The ornament of design for a pontoon boat, as shown.
